GUN SIGHT

Grover C. Lee, Royal Oak, Mich.

Application February 17, 1954, Serial No. 410,870

1 Claim. (Cl. 33—58)

This invention generally relates to gun sights and particularly pertains to a new, novel, and inventive simplified rear gun sight capable of quick, accurate elevation and deflection adjustment.

The art has many rear gun sights which are capable of adjustment for elevation and deflection to compensate for height and drift deviation, however, the several devices of the prior art have not proven entirely satisfactory inasmuch as they are complicated in design and construction, expensive to manufacture, difficult to use and adjust, and difficult to maintain in adjustment.

With the foregoing in view, the primary object of the invention is to provide an adjustable rear gun sight which is simple in design and construction, inexpensive to manufacture, easy to use and adjust, and capable of maintaining adjustment.

An object of the invention is to provide a rear gun sight which can be used and adjusted by the average sportsman as well as the expert rifleman.

An object of the invention is to provide a rear gun sight which can be fitted to all sizes of rifles and carbines without changes in the assembly or re-arrangement of parts.

An object of the invention is to provide a rear gun sight which has a base directly mountable on the gun barrel or breach which is pivotally mounted at its muzzle end, which is equipped with a micrometer deflection scale for reading against an index point on the gun, and which is equipped with an arcuate slot for swinging the breach end of the base.

An object of the invention is to provide a shoulder portion on the base having a micrometer threaded aperture midway between the front pivot and the breach scale so that pivoting the base moves the shoulder aperture one-half the distance indicated on the micrometer deflection scale to give fine adjustment.

An object of the invention is to provide a micrometer threaded neck portion threadable into the shoulder position.

An object of the invention is to provide a double-faced head on the neck portion having like eyepiece receiving sockets on either side thereof in the back to back relationship so that the head can be screwed up or down on the micrometer neck thread in the shoulder so that a half turn micrometer thread adjustment can be made with an eyepiece receiving socket being aligned parallel with the barrel.

An object of the invention is to provide a four-faced head on the neck portion having like eyepiece receiving sockets on four sides thereof in back to back relationship so that the head can be screwed up or down on the micrometer neck thread in the shoulder so that a quarter micrometer scale adjustment can be made with an eyepiece receiving socket being aligned parallel with the barrel.

These and other objects of the invention will become apparent by reference to the following description of an adjustable simplified rear gun sight embodying the invention.

tion taken in connection with the accompanying drawing, in which:

Fig. 1 is a side elevational view of a rifle with the inventive rear gun sight mounted thereon;

Fig. 2 is a relatively enlarged side elevational view of the inventive gun sight as seen in Fig. 1 approximately actual size, partly in cross-section showing the mounting;

Fig. 3 is a top plan view of the device as seen in Fig. 2;

Fig. 4 is a cross-sectional view of the device taken on the line 4—4 of Fig. 2;

Fig. 5 is a cross-sectional view of the neck and head portions;

Fig. 6 is a top plan view of the four-sided modification of the device facilitating $\frac{1}{4}$ micrometer elevation adjustment and

Fig. 7 is a side elevational view of the device seen in Fig. 6.

Referring now to the drawing wherein like numerals refer to like and corresponding parts throughout the several views, the gun sight 10 disclosed therein to illustrate the invention mounted on the gun 11 comprises a base 12 having a front or muzzle end aperture for receiving the mounting and pivot screw 13 and a rear or breach end arcuate slot 14 for receiving the mounting screw 15 so that the screws 13 and 15 can be loosened and the base 12 pivoted at the screw 13 with the arcuate slot 14 bypassing the screw 15 to permit adjusting the base for drift and other lateral compensations, the base 12 carries a scale 16 for reading against the index 17 located on the gun 11 so that the person using the device can determine the amount of adjustment he is making.

The shoulder 18 is mounted on the base 12 and is equipped with a central threaded aperture 19 preferably at a point equidistant between the center of the pivot screw 13 and the end 9 of the base 12 which carries the index 16 so that the shoulder aperture 19 moves half the distance indicated on the scale 16 when lateral compensation is made, thereby providing fine adjustment.

The threaded neck 20 is receivable in the shoulder aperture 19 and the head 21 is mounted on the neck 20 and is equipped with a transverse bore providing like faces 22 and 23 on either side of the head 21 so that the eyepiece 24 can be screwed or received in either side of the head 21, thereby facilitating half turn adjustment of the head 21 relative to the base 12 as hereinafter more fully explained. The base 12 is provided with a set screw 25 for clamping the neck 20 in its adjusted position.

Referring to Figs. 6 and 7, it will be noted that the modified head illustrated therein has two intersecting transverse bores 30 and 31, each having like faces 32, 33, 34, and 35 capable of receiving the eyepiece 24 therein, thereby providing quarter turn elevation adjustment as hereinafter more fully explained.

The scale 16 and the thread in the aperture 19 and on the neck 20 are preferably of known value such as the micrometer scale or the mil scale which is adapted easily for any length barrel in conjunction with the relationship and the distance to the front sight.

As an illustration, assuming the barrel is 36 inches long and that a mil is the angle defined by a yard variation at 1000 yards, the index 16 can be so scaled and the thread on the neck 20 can be so angulated. Obviously, these scales can be so graduated for any other distance such as 500 yards or 250 yards and in shooting at closer distances the finer adjustment can be made with the inventive device due to the fact that the head 21 is mounted midway between the pivot 13 and the index end 9 and due to the fact that the head is pivotally mounted it can easily be aligned in parallel relationship to the lateral adjustment.

In adjusting the device, such as shooting-in a gun, the lateral correction such as for drift and other sidewise

deviation can be made by loosening the screws 13 and 15 and sliding the end 9 of the base to the desired position and then retightening the screws 13 and 15. In adjusting the device for elevation, it is only necessary to remove the eyepiece 24 and loosen the set screw 25 so that the neck 20 can be freely turned in the bolts 18 of the base 12 or the eyepiece can be left in the head 21 to determine the amount of adjustment or turning of the neck 20 relative to the base 12 and then relocated in the rear aperture or face of the head 21 or 29, and it can easily be seen that a very fine adjustment can be achieved through half turns of the head 21 or quarter turns of the head 29, as desired.

Although but two embodiments of the invention have been shown and described in detail, it is obvious that many changes may be made in the size, shape, detail, and arrangement of the various elements of the invention within the scope of the appended claim. For example, the shoulder portion 18 can be eliminated and the base 12 made thicker, if desired, to provide sufficient up and down movement of the neck 20 relative thereto and the head provided with more intersecting transverse apertures such

as 3 or 4, thereby making the head hexagonal or octagonal in shape.

I claim:

5 A simplified rear gun sight comprising a base portion mountable on a gun having a threaded aperture intermediate the ends thereof, a neck threadable in said base aperture, a head on said neck having two transverse intersecting apertures having like opposed eyepiece receiving ends constituting like four-faces at 90° variation, an eyepiece receivable in any of said faces; said multi-faced head facilitating quarter turn adjustment of said neck in said base to raise and lower said head to compensate for elevation; and means for securing said neck in adjusted position.
